UNITED STATES PATENT OFFICE

WILLIAM MILLER DIGHT, OF JACKSON CENTER, PENNSYLVANIA.

SASH-HOLDER.

No. 893,904.

Specification of Letters Patent.

Patented July 21, 1908.

Application filed July 3, 1907. Serial No. 382,019.

To all whom it may concern:

Be it known that I, WILLIAM MILLER DIGHT, a citizen of the United States, residing at Jackson Center, in the county of Mercer and State of Pennsylvania, have invented certain new and useful Improvements in Sash-Holders, of which the following is a specification, reference being had therein to the accompanying drawing.

10 My present invention relates to improvements in sash holders, and has for its object a simple, durable and efficient device, adapted to be carried by the sash, and provided with means which are thrown into and 15 out of engagement with the window frame, to hold the window sash at any desired adjustment, or allow the window to be moved freely.

The main device is inclosed in a case, and 20 has two clamps or arms, which are normally held in engagement with the window frame by means of a spring, a cam operated by a handle and mounted in the casing, being operated to spread the clamps to release their 25 ends from the window frame. The clamps may be either provided with a roughened engaging surface, or may be pocketed upon their ends to receive a non-slipping substance, such as leather or rubber, or the window frame may have serrations or corrugations 30 to be engaged by the clamps.

To clearly illustrate my invention, I would refer to the accompanying drawings, in which:—

35 Figure 1 is a front elevation of the device in operable position, a portion of the casing being broken away to show the interior mechanism. Fig. 2 is a similar view with the clamp disengaged. Fig. 3 is a section 40 through one of the clamps, showing the non-slipping substance in place.

Referring to the drawings:—A designates the window frame and B the sash. Mounted upon the sash is the base plate 1 of the 45 casing 2, which is secured to the sash in any desirable manner. Passing through the casing and base plate is a rivet 3, which also serves as a pivot for the eyed ends 4, of the two arms or clamps 5, whose engaging ends 50 6, are at angles to the body, as shown, and are provided with receptacles 7 for the block 8, of non-slipping substance, such as rubber or leather. Mounted upon the pivot between the slots 9, of the ends 4, of the arms, 55 and have its terminals 10 projecting through

said slots and resting in the channels 11, of each arm, is the spring 12, which normally exerts a tension upon the terminals so as to bring the engaging ends of the arm together, as shown in Fig. 1. By this means, the engaging ends are always held in engagement with the window frame, and should the frame be provided with serrations or corrugations, the engaging ends are similarly provided and thus firmly lock or hold the sash. 60 As shown, the block 8 engages the frame and holds the sash.

Should it be desired to release the engaging ends of the arms from the frame, the handle 13 is operated and assumes the position 70 shown in Fig. 2, at which point the cam or double-end bar 14, carried within the casing between the terminals of the arms, engages the said arms upon their inner faces and pushes the terminals apart and this action 75 brings the engaging ends within the casing and away from the frame, so that the window sash may be freely moved up or down. When it is desired to release the arms from engagement with the cam, a slight touch 80 upon the handle will move the cam or bar so that it will be at an angle to the terminals, at which point the spring will project the engaging ends of the arms, engaging the frame, and causing the cam or bar to lie parallel 85 with the terminals.

What I claim as new, is:—

In combination with a window frame and sash, of a sash holder mounted upon the sash and opposed to the frame, and comprising a 90 base plate, a casing secured thereto and open toward the frame, a pair of arms having slotted inner ends and frame engaging outer ends, a common pivot for securing the slotted ends of the arms within the casing, a spring 95 having a coil mounted on the pivot between the arms and having its terminals entering the slots of the arms to normally hold the free frame engaging ends in engagement with the frame, a bar pivotally mounted within 100 the casing intermediate of the ends of the arms, and a handle for turning the bar to spread the free ends of the arms apart and release the same from the window frame.

In testimony whereof I affix my signature 105 in presence of two witnesses.
